UNITED STATES PATENT OFFICE.

CHARLES BLAGBURN, OF SAN FRANCISCO, CALIFORNIA.

CAISSON FOR SUBAQUEOUS WORK.

SPECIFICATION forming part of Letters Patent No. 694,939, dated March 11, 1902.

Application filed May 9, 1901. Serial No. 59,438. (No model.)

To all whom it may concern:

Be it known that I, CHARLES BLAGBURN, a citizen of England, residing in the city and county of San Francisco, State of California, have invented certain new and useful Improvements in Caissons for Subaqueous Work; and I do hereby declare the following to be a full, clear, and exact description of the same.

10 The present invention is more especially applicable for the removal of what is known as "hard-pan" in connection with the work of mining under water, although it is adapted for any class of subaqueous work where it is desired to remove material from within the 15 caisson without liability of the air escaping therefrom during the work of such removal.

In order to comprehend the invention, reference should be had to the accompanying 20 sheet of drawings, wherein—

Figure 1 is a longitudinal sectional view in side elevation; and Fig. 2 is a front view in elevation, the caisson and water-seal tube being partly in section.

25 The letter A is used to indicate the caisson. (Shown in Fig. 1 of the drawings as being submerged and rests upon the bottom or river-bed A'.) Said caisson is provided with an entrance-tube B, communication being established between the interior of the casing and the entrance-tube by a hinged air-lock door B'. The entrance-tube may be said to constitute a continuation of the air-lock C, which lock is closed by the vertically-movable air-lock door C'. In gaining admission to the air-lock it is necessary to admit of a person entering therein. While said door is opened the air-lock door B' is held upward, so as to close communication between the entrance-tube and 35 the interior of caisson. This is to prevent the escape of air from within the interior of the caisson. After the door C' has been closed then the door B' is swung open, so as to permit of entrance being had to the interior of 40 the caisson.

Air under pressure is supplied to the interior of caisson by supply-pipe C², which supply-pipe leads from any suitable source of power. (Not shown.)

45 Within the caisson at any convenient point is arranged a hopper E', to which is connected

tube E. One portion of the tube extends within the hopper E' to a point near its bottom, said extension forming a wall 1. The tube E extends above the water-line for a 55 short distance, so that the water therein will be such as to resist the air-pressure within the caisson. As the caisson is submerged the water is forced therefrom by the pressure of the air therein, the pressure of which maintains the water in the tube E at a given height or level. The water thus contained in the tube forms a perfect water seal, within which the hereinafter-described discharge mechanism works and which prevents the escape of 60 air from within the caisson.

Near the bottom of the hopper is arranged the chain-wheels 2, over which travel the endless chain-carriers 3. These carriers work within the seal-tube E and over guide-wheels 70 4 and chain-wheels 5, held within frame 6. To the endless carriers the buckets 7 are attached at proper intervals. These buckets and chains constitute an endless chain and bucket elevator.

75 The shaft 8, to which the chain-wheels 5 are secured, is driven by means of a belt working over belt-wheel F', attached to said shaft. The belt is driven from any suitable power mechanism. (Not shown.)

The workman located inside of the caisson throws the excavated material directly into the hopper E', there being a grid G arranged to catch or hold back boulders too large to be raised by the endless chain and bucket elevator. Such material as passes through the grid falls to the bottom of the hopper and is taken up by the buckets 7 during the travel of the endless carrier and carried upward through the water-seal tube and over the chain-wheels 85 5. As carried over these chain-wheels the material contained therein is discharged into chute H, by means of which it is delivered to a suitable place of deposit. If the material thus removed from the river-bottom be gold-bearing, the same is discharged by the chute 90 into a suitable receptacle, from which it is taken and treated in order to recover the valuable particles.

95 The chain-wheels 2 are mounted in slide-bearings, which are controlled by the take-up mechanism 9. By means of this take-up mech-

anism the slack of the chain carrier is compensated for.

Inasmuch as the travel of the endless chain and bucket elevator through the tube E is liable to remove a portion of the water therein, and thus reduce the pressure of the water seal, it is deemed advisable to provide means whereby the water-level is automatically maintained. To this end there is located 10 within the water seal a float I, the float-rod I' thereof being attached to one end of a fulcrumed lever K. The inner or free end of said lever is connected to the outlet-valve a of water-supply tank K' by means of chain a'. 15 The outlet b of this tank communicates with water-seal tube E. Consequently the moment the water in said tube has fallen below a given point the float descends and draws therewith the float-rod and lifts the valve a, so as to 20 seal or open same and permit the water to flow into the water-seal tube, thus maintaining the water therein at approximately a given level. It will be understood that as the water reaches the proper level in the water-seal 25 tube that the float raises and the outlet-valve of the supply-tank is closed.

For the purpose of raising or removing boulders from within the caisson the wire rope or cable L is employed. This cable extends 30 through the air-lock C and is provided at one end with a hook L', by means of which the cable is fastened around the boulders. However, any suitable means may be employed for the removal of boulders or the like, 35 that illustrated being the simplest for the purpose.

The essential feature of the invention resides in the employment of discharge mechanism for the excavated material in combination with the water-seal closure between the interior of the caisson or working compartment and the discharge of the excavated material.

Having thus described the invention, what 45 is claimed as new, and desired to be protected by Letters Patent, is—

1. A caisson having in combination a working chamber, a water-sealed U-shaped discharge-conduit suspended from a point above 50 the working chamber, one arm of said chamber extending without said chamber and the other arm being supported by the lower end of the said first-mentioned arm and opening within the working chamber.

55 2. A caisson, having in combination, a working chamber having an open lower end, a water-sealed conduit extending from the working chamber to a point above the level of the water and means for automatically varying

the height of the water column controlling 60 the water seal, substantially as set forth.

3. A caisson, having in combination, a working chamber having an open lower end, a discharge-conduit extending from the working chamber to a point above the level of the water and provided, within the working chamber, with a receiving branch having an open 65 upper end and means for automatically maintaining the water within the conduit at a height not less than the level of the water 70 outside of the conduit, substantially as described.

4. The combination with a caisson for subaqueous work having an opening in its lower portion, of a receiving-hopper for the excavated material, a water-seal conduit integral 75 with said hopper, and a chain and bucket carrier adapted to work through said conduit for removing the excavated material, substantially as described.

5. The combination with a caisson for subaqueous work, of a receiving-hopper for the excavated material, a water-seal tube connected therewith and projecting beyond the caisson above the water-line and an endless 85 chain and bucket carrier working therein and through the water seal for the removal of the excavated material.

6. The combination with a caisson for subaqueous work, of a water-seal closure for the 90 outlet of the excavated material, including a hopper and a conduit secured together, and a chain and bucket conveyer working through said water seal for the removal of the excavated material.

7. The combination with a caisson for subaqueous work, of a water-seal closure for the outlet of the excavated material, devices working 95 through said water seal which receive and remove the excavated material, and means 100 whereby the water seal is automatically maintained at approximately a given level.

8. The combination with a caisson for subaqueous work, of a receiving-hopper for the excavated material, a tube secured thereto 105 and projecting beyond the caisson above the water-line, a water seal within said tube and hopper, means for automatically maintaining the water seal at approximately a given level, and devices working through the water seal 110 for removing the excavated material from within the ore-receiving hopper.

In witness whereof I have hereunto set my hand.

CHARLES BLAGBURN.
